UNITED STATES PATENT OFFICE

WALTER F. STIMPSON AND WILLIS E. FINCH, OF LOUISVILLE, KENTUCKY; SAID FINCH ASSIGNOR TO SAID STIMPSON

SCALE

Application filed January 26, 1925. Serial No. 4,834.

Our invention relates to scales and more particularly to constructions designed for an enameled finish.

In the present state of the art of scale construction it is usual to secure associated parts to each other by the use of screws or bolts. Where, however, the parts of the scale are given a vitreous enamel finish the localized stresses produced by such screws or bolts frequently cause a chipping of the enamel and consequent marring of the finish. To avoid such defect, we have designed a construction dispensing with such securing means and substituted therefor yieldable clips which may be readily engaged or disengaged without injury to the finish. These clips vary in construction according to the particular design of scale or the parts thereof which are removably secured but in each modification 20 a resilient yieldable element is used in place of the screws or other fastening devices heretofore used.

In the drawings,—

Figure 1 is a sectional side elevation of a 25 cylinder scale embodying our invention;

Figure 2 is a front elevation of a modified type of scale having a fan-shaped chart housing;

Figures 3 and 4 are cross-sections of the 30 construction shown in Fig. 2;

Figure 5 is a sectional plan view showing the platform and means for securing the same to the platform-securing frame;

Figure 6 is a section on the line 6—6, Figure 35 5;

Figure 7 is a perspective view showing one of the end cover plates for the cylinder housing;

Figure 8 is a section therethrough;

Figure 9 is a section showing the securing means for one of the removable cover plates of the pedestal; and

Figure 10 is a similar view of another cover plate showing the collapsible handle therefor.

Figure 11 is a section on the line 11—11 of Fig. 5.

In the construction shown in Figures 1 and 5 to 10 inclusive, the scale is of the cylinder 50 type comprising a platform frame A, and a

pedestal including the lower reduced portion B and the upper cylindrical portion C. To provide access to the cylinder the ends of the housing therefor are removable, being usually secured in position by screws or bolts. 55 With our improved construction, however, these ends D are formed with flanges E telescopically engaging the ends of the cylinder housing C and are also provided with one or more spring clips F for engaging a part 60 such as the frame bar G and yieldably holding the cover in position.

It is also usual to provide removable panels or cover plates on the lower pedestal portion, for the purpose of gaining access to the 65 pendulum weight or other parts of the weighing mechanism. Such panel cover plates H we have secured by similar means to that used for the cylinder ends D, viz., yieldable spring clips I which engage lugs J on the opposite 70 side of the opening in the pedestal. To facilitate detachment of the panel cover H, a handle K is placed thereon, this preferably consisting of a flat knob K having a shank K' passing through an aperture in the plate with 75 a spring K² sleeved thereon and abutting against the collar K³. This spring will normally hold the knob close to the cover plate, but will permit of its being drawn outward when required to remove the panel. 80

Below the panel cover plates H are usually smaller covers L for closing the opening in the base of the pedestal providing access to other parts of the mechanism. These plates L, as shown, are removably secured by a clip 85 M which is in the form of a strip of resilient metal centrally attached to said cover L and having one end M' adapted to underlap the wall of the pedestal and the opposite end bent to form a yieldable flange M². Thus by first 90 inserting the end M' into engagement with the wall of the housing and then pressing the cover plate inward the flange M² will yield to enter into engagement with the opposite wall. With the type of scale shown 95 in Figs. 2, 3 and 4 glass panels N are secured to the fan-shaped housing O by glass-holding frames P. These frames, instead of being secured by screws, as is usual, are so fashioned as to overlap and seat upon the housing 100

O and are provided with spring clips Q for retaining the same. As shown in Figure 3, one of the frames P is provided with a spring tongue Q' which yieldably engages a cooperating spring tongue Q² on the member O. In Figure 4 the spring clip Q³ is secured to the frame O and engages a lug Q⁴ on the frame P. Figures 5 and 6 show the scale platform R in engagement with the platform supporting frame S. These parts are secured to each other by providing the frame S with the radially-projecting rounded lugs T for engaging the depending channeled flange U on the platform R. On the opposite side of the frame S there is arranged a spring bar V which is secured by depending posts or pins W passing through radially slotted lugs W' on said frame. The posts or pins W have sleeved thereon the springs W² which bear at one end on a clamping plate W³ and at their opposite ends against a nut W⁴. This bar V is of such extent that the opposite ends thereof may be engaged in the channeled flange U of the platform R and by then applying downward pressure upon said platform it may be snapped into engagement with the lugs T. This will securely attach the platform to the frame without the use of bolts, screws, or other equivalent fastening means. With all of the various constructions above described, as well as with many other equivalent constructions, the associated parts of the scale are removably secured to each other by yieldably resilient clips which will not in any way injure the enameled finish.

What we desire to claim is:

1. In a scale, the combination with a hollow pedestal and a cylinder housing at the upper end thereof, of a removable end plate for said cylinder housing provided with a marginal flange for telescopically engaging said housing, and a spring clip for retaining said end plate upon said housing.
2. In a scale, the combination with a hollow frame having an aperture therein and a removable cover-plate for such aperture seated upon said frame, of a disappearing knob for said cover-plate.
3. In a scale, the combination with a hollow frame having an aperture therein and a removable cover-plate for such aperture seated upon said frame, of a knob having a shank passing through an aperture in said plate and a spring sleeved upon said shank upon the inner side of said plate normally holding said knob in close contact with the plate but permitting of its being drawn outward therefrom.
4. In a scale, the combination with a hollow frame having an outer enameled surface, the said hollow frame being provided with an aperture, of a cover plate for the said aperture, the said cover plate having its outer surface enameled and means for detachably securing the cover plate to the said frame to

close the said aperture, the said means being so arranged as to be entirely free from contact with the said enamel surfaces of the frame and cover plate.

5. In a scale, the combination with a hollow pedestal having an aperture therein, of a removable cover plate for the aperture seating upon the said pedestal, a frame bar within the pedestal, and means carried by the said cover plate and engageable with the said frame bar for detachably securing the cover plate to the said pedestal, the said means being housed entirely within the hollow pedestal when the cover plate is on its seat.

6. In a scale, the combination with a hollow frame having an aperture therein, of a removable cover plate for said aperture seating upon said frame, a spring clip on the inner face of the said cover plate for retaining said cover plate upon said frame, and a cross member within said frame embraced by the said clip.

7. In a scale, the combination with a hollow pedestal having an aperture therein, of a panel cover plate for said aperture marginally seated upon said aperture, a spring clip on the inner face of and spaced from the marginal portions of the cover plate for retaining said cover plate on the pedestal, and a cross member within the said pedestal embraced by the said clip.

In testimony whereof we affix our signatures.

WALTER F. STIMPSON.
WILLIS E. FINCH.
